Corporation, New Haven, Conn., a corporation
of Connecticut

Application September 27, 1950, Serial No. 12,370

Term of patent 14 years

(Cl. D52—2)

To all whom it may concern:

Be it known that we, Henry M. Dunn and David Oles, citizens of the United States, residing at New Haven, in the county of New Haven and State of Connecticut, have invented a new, original, and ornamental Design for an Apparatus for Cleaning Automobile Radiators and the like, of which the following is a specification, reference being had to the accompanying drawing, forming part thereof.

Fig. 1 is a perspective view of an apparatus for cleaning automobile radiators and the like as seen from the front and showing our new design;

Fig. 2 is a side elevation thereof; and

Fig. 3 is a top plan view of the apparatus.

We claim:

The ornamental design for an apparatus for cleaning automobile radiators and the like, substantially as shown.

HENRY M. DUNN.
DAVID OLES.
